COMBINED BEVERAGE BOTTLE, CLOSURE CUP AND HANDLE

Varam M. Kazaz, Condomino dei Fiori,
Suna di Verbania, Novara, Italy

Filed June 27, 1968, Ser. No. 12,524

Term of patent 14 years

Int. Cl. D7—99

U.S. Cl. D44—1

FIG. 1 is a side elevational view partly in section of a combined beverage bottle, closure cup and handle showing my new design;

FIG. 2 is a top plan view.

I claim:

The ornamental design for combined beverage bottle, closure cup and handle, as shown.
